UNITED STATES PATENT OFFICE.

WILLIAM A. REYNOLDS, OF CLEVELAND, OHIO, ASSIGNOR TO THE OHIO RUBBER COMPANY, OF CLEVELAND, OHIO, A CORPORATION OF OHIO.

DESIGN FOR A BULB FOR HYDROMETER SYRINGES.

Application filed February 11, 1927. Serial No. 20,699. Term of patent 7 years.

To all whom it may concern:

Be it known that I, **WILLIAM A. REYNOLDS**, a citizen of the United States, residing at Cleveland, in the county of Cuyahoga and State of Ohio, have invented a new, original and ornamental Design for Bulb for Hydrometer Syringe, of which the following is a specification, reference being had to the accompanying drawing, forming a part thereof.

In the drawing, Fig. 1 is a plan view; Fig. 2 is an end view looking toward the open end of the bulb; and Fig. 3 is an end view looking toward the closed end of the bulb, showing my new design.

I claim:

The ornamental design for bulb for hydrometer syringe substantially as shown.

WILLIAM A. REYNOLDS.
